CLAIM

We claim the ornamental design for a shield holder, as shown and described.

DESCRIPTION

FIG. 1 is a perspective view of a shield holder showing our new design;

FIG. 2 is a top plan view thereof;

FIG. 3 is a right side view thereof, the left side being a mirror image;

FIG. 4 is a front view thereof;

FIG. 5 is a rear view thereof;

FIG. 6 is a bottom view thereof;

FIG. 7 is a perspective view of a second embodiment thereof;

FIG. 8 is a top plan view of FIG. 7;

FIG. 9 is a right side view of FIG. 7;

FIG. 10 is a front view of FIG. 7;

FIG. 11 is a rear view of FIG. 7; and,

FIG. 12 is a bottom plan view of FIG. 7.
